(57) **CLAIM**

I claim the ornamental design for a lamp with hourglass globe, as shown and described.

DESCRIPTION

FIG. 1 is a top perspective view taken of the lamp with hourglass globe showing my new design;

FIG. 2 is an exploded top perspective view of the lamp with hourglass globe;

FIG. 3 is a top view thereof;

FIG. 4 is a bottom view thereof;

FIG. 5 is a front view thereof;

FIG. 6 is a left side view thereof; and,

FIG. 7 is a rear view thereof.

The broken line disclosure represents portions of the lamp which form no part of the claimed design.
